UNITED STATES PATENT OFFICE.

EDWIN L. LLOYD, OF PHILADELPHIA, PENNSYLVANIA.

WINDOW-SCREEN.

SPECIFICATION forming part of Letters Patent No. 728,121, dated May 12, 1903.

Application filed September 10, 1902. Serial No. 122,840. (No model.)

To all whom it may concern:

Be it known that I, EDWIN L. LLOYD, a citizen of the United States, residing in Philadelphia, Pennsylvania, have invented certain improvements in Window-Screens, of which the following is a specification.

My invention relates to that class of window-screens which are applied to the window-frame alongside of the sash instead of between the bottom of the sash and the sill, the lower bar of the sash bearing against the face of the top bar of the screen when the sash is raised, so as to form a close joint therewith and prevent the passage of insects between the two.

One object of my invention is to construct a screen of this class which is applicable to window-frames of different widths, other objects being to firmly guide the adjustable expansion-strips of the screen, to render said expansion-strips self-expanding, and to produce a screen which will present a neat appearance, the netting being wholly unobstructed and the springs which effect the projection of the expansion bars or strips being concealed from sight and protected from exposure to the weather.

In the accompanying drawings, Figure 1 is a face view, partly in section, of a window-screen constructed in accordance with my invention. Fig. 2 is a top or plan view of the same, illustrating also the grooved guides or retainers on the window-frame to which the screen is adapted. Fig. 3 is a section on the line *a a*, Fig. 1. Fig. 4 is an enlarged transverse section on the line *b b*, Fig. 1. Fig. 5 is an enlarged transverse section on the line *c c*, Fig. 1. Fig. 6 is a sectional view illustrating a modification of the invention; and Fig. 7 is a transverse section on the line *d d*, Fig. 6.

Referring first to the screen shown in Figs. 1 to 5, it will be noted that the fixed frame of the screen comprises end bars 1, top and bottom bars 2, and supplementary top and bottom bars 2^a, and each of the adjustable end frames of the screen comprises an expansion-strip 3 and guiding joint-forming bars 4, secured to and projecting inwardly from said strip 3 at the top and bottom of the screen. The netting 5 is secured to the bars 1 and 2 of the fixed frame, the expansion-

strips 3 overlapping the netting at the ends of the frame, so as to slide freely back and forth over the same.

The supplementary top and bottom bars 2^a of the fixed frame have longitudinal grooves 6 formed therein for the reception of ribs 7 on the bars 4, which bars are in contact with the top and bottom bars 2 of the fixed frame, as shown in Fig. 1. The inwardly-projecting rib of each bar 4 has formed in it a longitudinal slot 8 for the reception of a vertical pin 9, carried by the bar 2^a, this pin-and-slot connection preventing either the lateral or longitudinal removal of the sliding frames of the screen from the fixed frame of the same and also limiting the extent to which the sliding frames can be projected, contact of the inner ends of the top and bottom bars 4 of the sliding frames limiting the approach of the latter. The rib 7 of each bar 4 also has formed in it another slot 10, which contains a spring 11, bearing at its outer end against the shoulder at the end of the slot and at its inner end against a block 12, secured to the bar 2^a of the fixed frame of the screen, the springs 11 serving to project the bars 4 and the end strips 3 carried thereby to the full extent permitted by the contact of the pins 9 and blocks 12 with the shoulders at the inner ends of the slots 8 and 10.

The screen may be held in position in the window-frame by frictional contact of the end strips 3 with the sides of the window-frame; but it is preferable to provide said window-frame with grooved guide-bars 13 for the reception and guidance of the strips 3, as shown in Fig. 2, the top and bottom bars 4 of the sliding frames being in this case cut away at their outer ends, as shown in Figs. 1 and 2, in order to permit the guides to properly overlap the strips 3.

In assembling the parts of the screen the netting is first applied to the bars 1 and 2 of the fixed frame, and the top and bottom bars 2^a are then secured to the bars 2. The springs 11 and blocks 12 are then inserted in the slots 10 of the ribs 7, and said ribs are slid longitudinally into the grooves 6 of the bars 2^a until the inner ends of the bars 4 meet at the center of the screen, the strips 3 being then fully retracted. The blocks 12 are then secured to the bars 2^a, preferably by nails or

pins 14, and the pins 9 are inserted in proper position for restricting the expansion of the sliding frames of the screen by contact with the shoulders at the inner ends of the slot 8.

5 The assembling of the parts of the screen can thus be quickly effected without the employment of skilled labor, thereby reducing the cost of this element of manufacture.

If the ribs 7 of the bars 4 are beveled or 10 undercut, the use of the pins 9 and slots 8 can be dispensed with, the projection of the end strips 3 being limited by contact of the shoulders at the inner ends of the slots 10 with the blocks 12 or with the pins 14 when said 15 block is not used. In some cases the screen can be made with an expansion-strip at one end only; but the construction shown is preferred.

The screen presents a very neat appearance, the netting is unobstructed throughout 20 the entire area of the screen, and the various springs which effect the expansion of the movable elements of the screen-frame and the stops for limiting such expansion are hidden 25 from view and protected from access, so that they cannot be tampered with by ignorant or mischievous persons or injured by exposure to the weather. The screen, moreover, is strong and durable, the long top and bottom 30 bars 4 of the movable members of the screen-frame providing an efficient support for said movable members of the frame upon the fixed frame, whereby the expansion-strips 3 at the ends of the screen are firmly guided in their 35 movements and cannot be warped or twisted out of their proper position. Hence the free sliding movement of these expansion-bars is never interfered with.

When the screen is applied to the window-frame, the bars 2 and 4 at the top of the frame bear against the lower rail of the sash, as 40 shown in Fig. 4, the bars 2 bridging the gap between the separated inner ends of the bars 4 and said bars 4 filling the space between 45 the rail of the sash and the expansion-strips 3, where the latter are projected beyond the bars 1 of the fixed frame at the ends of the screen, a close joint being thus produced and the passage of insects between the sash-frame 50 and the bars of the screen effectually prevented.

In that embodiment of my invention shown in Figs. 6 and 7 a wire 4^a is used in place of the bar 4, this wire 4^a being secured to the 55 end strip 3 and adapted to a groove 6, formed in the bar 2^a of the fixed frame. A spring 11, contained in the groove, acts upon a lug 15, projecting from the wire, and thus serves to project the end strip 3.

Having thus described my invention, I claim and desire to secure by Letters Patent—

1. The combination of the fixed frame of the screen having a bar with a groove in one of its side faces and an expansion end strip 65 having a guiding and joint-forming bar adapted to said groove and flush with that face of the screen-frame bar in which the groove is formed, substantially as specified.

2. The combination of the fixed frame of 70 the screen having a bar with a groove in one of its side faces, an expansion end strip having a guiding and joint-forming bar adapted to said groove and flush with that face of the screen-frame bar in which the groove is 75 formed, and a spring acting upon said guide-bar so as to project the end strip, substantially as specified.

3. The combination of the fixed frame of 80 the screen having a bar with a groove in one of its side faces, an expansion end strip having a guiding and joint-forming bar adapted to said groove and flush with that face of the screen-frame bar in which the groove is formed, and a pin-and-slot connection 85 between said guide-bar and the bar of the fixed frame whereby the two are laterally confined together, substantially as specified.

4. The combination of the fixed frame of 90 the screen having a bar with groove in one of its side faces, the expansion end strip having a guiding and joint-forming bar adapted to said groove and flush with the face of the screen-frame bar in which the groove is formed, said bar having a slot therein, a spring 95 contained in said slot and a bearing for said spring carried by the bar of the fixed frame, substantially as specified.

5. The combination of the fixed frame of 100 the screen having a bar composed of two parts 105 confining the netting between them, one part being less in height than the other and the other part having in its projecting portion a face-groove, an expansion-strip provided with a bar bearing against the face of said projecting bar, and having a projecting rib adapted to the groove therein, said guide-bar being also flush with the face of the other bar of the frame, and means for laterally confining 110 said expansion-strip bar to the bar of the screen-frame, substantially as specified.

In testimony whereof I have signed my name to this specification in the presence of two subscribing witnesses.

EDWIN L. LLOYD.
